PACKAGING CONTAINER

Herbert J. Wanderer, Elmhurst, Ill., assignor to Illinois
Tool Works Inc., Chicago, Ill., a corporation of Delaware

Filed June 25, 1963, Ser. No. 75,518

Term of patent 14 years

(Cl. D58—17)

FIG. 1 is a perspective view of a packaging container showing my new design;

FIG. 2 is a side elevational view, partially in section, of the container shown in FIG. 1; and

FIG. 3 is a top plan view.

The dominant features of my design reside in the portions shown in full lines.

The broken lines are eliminated from FIGS. 1 and 3 for convenience of illustration.

I claim:

The ornamental design for a packaging container, as shown and described.
